RESUSCITATION APPARATUS

James H. Meuler, Oconomowoc, Wis.

Application June 16, 1947, Serial No. 754,999

15 Claims. (Cl. 128—29)

1

The invention relates to resuscitation apparatus to resuscitate a victim of suffocation, lung paralysis, immersion, carbon monoxide, cardiac conditions, acute respiratory infections, drugs, convulsions, asthma, electric shock, and other conditions resulting in respiratory failure or retardation.

It has been established that the various prone pressure methods of resuscitation are unsatisfactory because of the inability of lay persons to carry them out, and because when properly carried out, there is insufficient respiratory exchange during the cycle. It has been found that resuscitation carried out by placing a patient on a tiltable support and rocking this support is far more effective than former methods, but up to the present apparatus to effect the tilting method have been unsatisfactory. Mechanical drives for the tilting mechanism are not satisfactory because of the ever present chance of mechanical failure and of the cost and bulkiness of such equipment. To be successful an apparatus for carrying out the tilt method must be inexpensive, simple, readily portable and easy to operate. The object of the present invention is to provide an apparatus that satisfies these requirements and more particularly one which may be carried in knockdown condition to the scene of use, may be easily set up, consists of few parts, and embodies a timer whose operation is readily understood.

The invention further consists in the several features hereinafter described and more particularly defined by claims at the conclusion hereof.

In the drawings:

Fig. 1 is a side elevation view of a resuscitation apparatus embodying the invention;

Fig. 2 is a plan view of the apparatus;

Fig. 3 is an elevation view of the apparatus;

Fig. 4 is a detailed vertical sectional view taken on the line 4—4 of Fig. 1;

Fig. 5 is a detailed vertical sectional view taken on the line 5—5 of Fig. 4;

Fig. 6 is a side elevation view of the fixed support in knockdown position;

Fig. 7 is an end elevation view of the collapsed fixed support;

Fig. 8 is a side elevation view of the movable support in knockdown position;

Fig. 9 is a plan view of the movable support in knockdown position;

Fig. 10 is a detailed side elevation view showing a modified form of hinge mounting, parts being broken away;

Fig. 11 is a detailed vertical sectional view taken on the line 11—11 of Fig. 10;

2

Fig. 12 is a vertical sectional view taken on the line 12—12 of Fig. 11;

Fig. 13 is an enlarged plan view of one of the handles of the movable support showing the timer exposed;

Fig. 14 is a detailed vertical sectional view taken on the line 14—14 of Fig. 13;

Fig. 15 is a detailed elevation view of a leg foot-ing member;

Figure 16 is a vertical sectional view taken on line 16—16 of Figure 13.

Referring to the drawings, the device includes a collapsible fixed support 16 and a collapsible movable support 17 medially pivotally mounted on said fixed support.

Referring to Figs. 1 to 9, the fixed support 16 includes spaced pairs of legs 18. Each pair of legs 18 is pivotally connected together by a pivot comprising a threaded sleeve bolt 19 receiving within it the threaded shank 20 of a bolt 21 which shank engages a spring lock washer 22 disposed at the inner end of the sleeve of the bolt 19 as shown in Fig. 4, the heads of the bolts 19 and 21 forming stop shoulders between which the rounded upper ends 23 of the legs 18 are disposed, it being noted that the legs are so shaped that the main portion 24 thereof is offset at the ends 23 and that the foot portions will have a flat floor-engaging end 26. These ends 26 may simply rest on the ground or other support, or on shipboard may be placed in appropriate leg-receiving recesses, or as shown in Fig. 15 rubber suction foot pads 27 may be mounted on the legs.

Each pair of legs is held in spread apart position by suitable brace links 28 pivotally connected together at their inner ends by pins 29 and pivotally connected at their outer ends by pins 30 to the legs.

For holding the pairs of legs 18 in laterally spaced positions, sets of suitable brace links 31 are associated with the corresponding leg of each pair. Each set of links 31 embody link members 32 pivotally connected together at their inner ends by pins 33 and pivotally connected at their outer ends by pins 34 to the legs as shown in Fig. 3. One of the links 28 or 32 may be longer than the other as shown in Figs. 6 and 7 and provided with a projection 35 to engage in a recess 36 in the shorter link when the links are in extended or alined position as shown in Figs. 1 and 3. The upper set of links 31 are positively locked together by having registering holes 30' in the shorter link 32 and the extended end of the other link 32 adapted to receive a locking pin 25 carried by a keeper chain 25. Also in order to further brace

these legs in the extended position of the brace links 31, a chain 33' is connected at each of its ends to the sides of the oppositely disposed legs 18 adjacent their pivots, as shown in Fig. 3, and is connected intermediate its ends to the pivot 33 for the upper set of brace links 31.

With the above arrangement, legs are held in fixed operative position when the links are extended, and when the links are collapsed, the legs may be folded together in pairs as shown in Fig. 6 and the pairs of legs then folded together as shown in Fig. 7, thus making a very compact bundle for the fixed support.

The movable support 17 is in the form of a stretcher having side frame members 37 to which a canvas top 38 is secured, said members being held in laterally spaced position with the top 38 in stretched condition by collapsible end braces 39, each comprising a pair of links 40 pivotally connected together at their inner ends by pins 41 and at their outer ends to the members 37 by pins 42. The frame members 37 are also preferably collapsible so as to form two half-frame members 43, and for this purpose one of the frame members 43 is fixed to a side plate 44, and the other frame member 43 is pivotally connected to this fixed member by a hinge 45 which has one of its hinge plates mounted on the top end of the other member 43. The frame members 43 together with their braces 40 are shown in collapsed condition in Figs. 8 and 9, and it will be noted that the plate 44 has a locking pin aperture 47 and the hinged member 43 a similar aperture 48 to receive a locking pin 49 when the members 43 are moved to the aligned position shown in Fig. 1, said pin being carried by the plate 44 through a flexible chain 50.

Each side plate 44 has a flanged head pivot member 51 anchored thereto which is adapted to rest in registering notches 52 in the associated pair of legs 18, so that the fixed support provides elevated spaced fulcrums on which the stretcher may tilt or oscillate, the frame members 37 having handles 53 at their ends.

When the stretcher is mounted on the fixed support, since the notches 52 are open notches, the pins or members 51 may be prevented from jumping out of said notches by chains 54, one chain anchored to each leg at 55 and having a ring 56 adapted to engage a hook 57 projecting from the end of the pin 51. These chains 54 may also be used to hold the stretcher in a substantial horizontal position by connecting their ringed ends with hooks 58 on the stretcher frame member and spaced equidistantly from the pin 51. For best results, the stretcher should be oscillated through an angle of about one hundred degrees, and for determining this angle stop means are provided shown in Figs. 4 and 5 as angle surfaces 21' found on the head of the bolt 21 and adapted to be engaged by the bottom of the plate 44 when it reaches the desired extreme position of tilt. Also for satisfactory results, the stretcher should be held in its upper and lower tilted position for a predetermined length of time, for example, two to three seconds in each position, and in order for even a lay operator to gauge this timing interval there is a gravity timer 59 disposed at each end of the stretcher frame, this timer comprising a closed tube 60 of glass or transparent plastic having a centrally disposed partition 61 of plastic with flats 62 to provide a timing restriction 63 through which the liquid, such as alcohol, disposed within said casing may flow from one end to the other, the time for this

transfer being the desired interval for holding the stretcher between tilts and in its tilted position. To protect the timer, when not in use, it is preferably mounted in a recess 64 in the handle and a cover plate 65 pivoted at 66 is adapted to be swung over the top of said recess. A small electric flashlight 60' is detachably mounted on one end of the frame members 37 adjacent its timer 60 to illuminate the same at night.

Instead of providing spaced pivot pins 51 on the stretcher for mounting in the notched portions of the legs, I may removably connect the pairs of legs 18 together by a cross shaft 67 as shown in Figs. 10 to 12 in which case said shaft has a threaded end 68 for engaging the internally threaded shank 69 of a bolt 70, similar to the bolt 19 and its shouldered end 71 abuts against a collar 72 that may be pinned or otherwise secured to one of the legs 18, said collar having tilt angle limiting stop pins 13 engageable with the bottom of the plate 44 in the extreme positions of tilt, the ends of the threaded shaft engaging spring lock washers 22' in the shanks 69 of the bolts 70. The plates 44 of the stretcher when the shaft 67 is used, carry fulcrum blocks 74 which form arcuate pivot surfaces that engage the shaft 67 and permit the stretcher to be rocked about the same, and the chains 54 engage a hook 57 on the plate 44 to prevent dislodgement.

For holding the patient on the stretcher, the canvas body 38 has crossed or diagonally disposed straps 75 secured intermediate their ends at 76 centrally of said body, and preferably offset slightly to one side of the fulcrum point of said stretcher, said straps being so spaced that they encircle the body above and below the hips and thus effectively prevent the patient from shifting lengthwise and laterally of the stretcher and permit of ready application to the patient, the offsetting taking care of the relative differences in weight of the body above and below the hips so that the center of gravity of the body is located substantially at the fulcrum point of said stretcher. Also straps 75, each secured intermediate its ends at 76 to the body of the stretcher and spaced toward one set of handles of the same are preferably provided, said straps being used to encircle the legs of the patient.

With the above arrangement, the patient in a prone position is placed on the stretcher and strapped thereto usually while the stretcher is in a lowered position, the loaded stretcher is then lifted up to a height sufficient to bring its pivots or fulcrum points into registry with the complementary fulcrum points of the fixed frame and the tilting back and forth of the stretcher with the patient thereon then proceeds the tilting action being done with the aid of the timer 59 as previously described, it being noted that with the tilting method pressure due to weight of body parts is alternately placed on the patient's diaphragm and then relieved therefrom causing the diaphragm to exert its effect on the lungs of the patient to simulate normal respiration.

I desire it to be understood that this invention is not to be limited to any particular form or arrangement of parts except in so far as such limitations are included in the claims.

What I claim as my invention is:

1. In a resuscitation apparatus, the combination of a collapsible fixed support comprising leg members pivotally connected together at one

of their ends in pairs and the pairs collapsibly cross connected, collapsible means for holding the other ends of the legs of each pair in spread apart condition, and a stretcher comprising longitudinal side frame members and a body carrying top, and means for detachably pivotally mounting said stretcher intermediate its ends on said fixed support.

2. In a resuscitation apparatus, the combination of a collapsible fixed support comprising leg members pivotally connected together at one of their ends in pairs and the pairs cross connected, collapsible means for holding the other ends of the legs of each pair in spaced apart condition, a collapsible stretcher comprising side members formed of half-length hingedly connected sections and a body carrying top member secured thereto, means for locking the hinged sections of each of said side members together in aligned position, and means for detachably pivotally mounting said stretcher intermediate its ends on said fixed support.

3. In a resuscitation apparatus, the combination of a collapsible fixed support comprising leg members pivotally connected together and provided with notches registering to form a fulcrum recess, a stretcher including frame members provided with medially disposed pivots for mounting in said recesses, and flexible restraining connections between said legs and said pivots.

4. In a resuscitation apparatus, the combination of two sets of leg members, the leg members of each set being pivotally connected together at one of their ends, means for holding the other ends of the leg members in a spread apart condition, collapsible means for connecting the sets of leg members in laterally spaced relation, a collapsible stretcher comprising side members formed of hingedly connected sections and a flexible body carrying top member secured thereto, means for holding the hinged sections in an aligned position, and means for pivotally mounting the stretcher on the pivoted end portions of said leg members.

5. In a resuscitation apparatus, the combination of a collapsible fixed support comprising sets of leg members, the leg member of each set having a pivot head offset from the body of the leg and a foot portion inclined inwardly from said body, the head portions of each set of legs arranged in abutting relation and the body portions of said legs being offset from said heads to align the leg members of each set together in a common plane, means pivotally connecting together the head portions of and said leg members in pairs, means for holding the pairs of legs in spaced relation, and a stretcher medially fulcrumed on said spaced sets of legs.

6. In a resuscitation apparatus, the combination of two sets of leg members, the leg members of each set being pivotally connected together at one of their ends, means for holding the other ends of the leg members in a spread apart condition, collapsible sets of upper and lower brace links connecting the sets of leg members in laterally spaced relation, the upper of said sets having means for locking the same in an operative position, and chain means connecting the upper set of brace members to the upper portions of the leg members to which said brace members are connected, and a stretcher comprising longitudinal side frame members and a body carrying top, and means for detachably pivotally mounting said stretcher intermediate

its ends on the upper ends of said sets of leg members.

7. In a resuscitation apparatus, the combination of a support, a stretcher medially fulcrumed to tilt on said support and including a body supporting top member, diagonally disposed straps secured centrally of the top member for engaging over the body of the patient above and below the hips thereof and acting to dispose the center of gravity of the body of the patient substantially at the fulcrum of the stretcher and transversely disposed straps secured intermediate their ends to said top member and spaced from said first named straps and adapted to engage over the legs of a patient.

8. In a resuscitation apparatus, the combination of a support, a stretcher medially fulcrumed to tilt on said support and including a body supporting top member, and diagonally disposed straps secured to the central portion of said top member and offset a short distance from the center of said top member for engaging over the body of the patient above and below the hips thereof to hold the body of the patient in a position in which its center of gravity is substantially at the fulcrum point of the stretcher.

9. In a resuscitation apparatus, the combination of a collapsible fixed support comprising leg members pivotally connected together at one of their ends in pairs and the pairs cross connected by collapsible means permitting movement of said pairs of legs into abutting relation, collapsible means for holding the other ends of the legs of each pair in spaced condition, and a stretcher comprising longitudinal side frame members and a body carrying top, and means for detachably pivotally mounting said stretcher intermediate its ends on said fixed support.

10. In a resuscitation apparatus, the combination of a fixed support, a collapsible stretcher comprising spaced sets of side members, the side member of each set being hingedly connected together at the central portion of said stretcher and a body carrying top member secured to said side members, a channel member provided with aligned apertures and secured to one of the side members of each set adjacent the hinged end thereof and adapted to receive and form a bottom support for the hinged end of the other of said side members which is provided with an aperture alignable with the apertures in said channel member, a locking pin passing through said apertures to lock said sets of side members in aligned position, and means for detachably pivotally mounting said stretcher intermediate its ends on said fixed support.

11. The structure as defined in claim 10 wherein the means for detachably pivotally mounting said stretcher intermediate its ends on the fixed supports includes fulcrums carried by said channel members.

12. In a resuscitation apparatus, the combination of two sets of leg members, each pivotally connected at one of their ends, collapsible means for holding the leg members of each set in spread apart condition, and collapsible connections between each set of leg members to form a collapsible fixed support, and a medially collapsible stretcher comprising hingedly connected frame members and a body carrying top, and means for detachably pivotally mounting said stretcher intermediate its ends on said fixed support.

13. In a resuscitation apparatus, the combination of a support, a stretcher medially fulcrumed

to tilt on said support and including a body supporting top member, said stretcher resting by gravity at its fulcrum points on said support, and means for retaining said stretcher against accidental removal from said support, said means including flexible connections between said support and said stretcher.

14. In a resuscitation apparatus, the combination of a stretcher, means for medially supporting said stretcher in a raised position for tilting movement, and a timer carried by the stretcher and cooperating therewith to time the dwell periods between tilts of said stretcher, said timer including a hollow straight tube body containing a liquid and having bottom portion of uniform section throughout its length and a medially disposed member above said bottom and forming a restriction.

15. In a resuscitation apparatus, the combination of a pair of spaced legs connected together to form an elevated fulcrum support, a stretcher fulcrumed on said support, and stop means on

said support adjacent the fulcrum point thereof of engageable with said stretcher to limit the extreme angle of tilt of said stretcher relative to said support.
